UNITED STATES PATENT OFFICE.

WILLIAM S. OSBORNE AND ELWIN C. BRYANT, OF ST. LOUIS, MISSOURI.

SYSTEM FOR PULVERIZING AND GRADING MATERIAL.

SPECIFICATION forming part of Letters Patent No. 710,604, dated October 7, 1902.

Application filed December 17, 1900. Serial No. 40,177. (No model.)

To all whom it may concern:

Be it known that we, WILLIAM S. OSBORNE and ELWIN C. BRYANT, citizens of the United States, residing at the city of St. Louis, in the 5 State of Missouri, have invented a certain new and useful Improvement in Systems for Pulverizing and Grading Material, of which the following is a full, clear, and exact description, such as will enable others skilled 10 in the art to which it appertains to make and use the same, reference being had to the accompanying drawings, forming part of this specification, in which—

Figure 1 is a view illustrating the apparatus employed in our improved system for pulverizing and grading material. Fig. 2 is a top plan view, partly in section, of a grader which initially operates upon the pulverized material. Fig. 3 is a vertical sectional view 20 through said grader. Fig. 4 is a top plan view, partly in section, of the separator. Fig. 5 is a vertical sectional view of the separator. Fig. 6 is a top plan view, partly in section, of the auxiliary separator; and Fig. 7 is 25 a vertical sectional view through said auxiliary separator.

This invention relates to a new and useful improvement in a system for pulverizing and grading material, the object being to separate 30 the particles of pulverized material from the air for the purpose of collecting the same, either in the form of finished product or as tailings to be returned to the grinding or pulverizing machine.

One of the objects of our present invention 35 is to employ as far as possible the same air as a vehicle for carrying the particles of material from the reducing-machine to the separating apparatus, said air after being freed 40 from said particles being returned to the machine to be used again. In this manner the small particles of material, which are so finely divided and so light as to be practically uncollectible, are kept in the system and by 45 being repeatedly subjected to a separating action will eventually take the path of the finished product.

With this object in view our invention consists in a system for pulverizing and grading 50 or separating material, such as will herein-after be described, and afterward pointed out in the claims.

In the drawings, A indicates a machine for reducing material to a finely-divided state, the material to be reduced being fed into said 55 machine through a closed hopper containing a feeding apparatus a. This reducing-machine may be of any desirable construction, and we have not, therefore, shown the details of the same in the drawings. 60

B indicates a spout leading from the top of the machine, into which the reduced material from the machine is received.

b is a valve in the spout B.

The spout B leads into what we have designated as a "grader" C, the details of which are shown in Figs. 2 and 3. This grader preferable consists of an octagonal casing having a conical lower portion discharging into a spout D, which spout connects with the feed 70 end of the machine and is provided with a valve d. The top of the grader is closed by a suitable cover.

E indicates a deflector secured to the grader in advance of the inlet-opening, said deflector 75 being attached at one side and to the top of the grader, an opening or space being provided at the opposite side and bottom of said deflector for the passage of the dust-laden air. In speaking of the "dust-laden air" we 80 wish to be understood as meaning the air coming from the grinding-machine which serves as a vehicle to carry the particles of reduced material in suspension. When this dust-laden air is introduced into the grader 85 C, it strikes the deflector E and is caused to take other than a straight path, being directed downwardly and to one side, so that the heavier particles will fall and the lighter particles will be carried by the air to and 90 through the escape-opening. Where two grinding-machines discharge into a single grader, we prefer to employ a pipe B' and a deflector E', which operate in substantially the same way as above described. However, 95 in this description we will assume that the pipe B' is a blind pipe having a cap provided at its end.

F indicates a discharge-pipe leading from the head of the grader opposite the inlet-pipe B, said pipe F connecting with the eye of a fan G. A suitable valve f is arranged in the pipe F. 100

H indicates a pipe leading from the fan G

into the head of a separator I. Before proceeding with a detailed description of this separator we will briefly describe the operation of the grader C. In using the term 5 "grader" in connection with this construction we do so, primarily, to distinguish this part of our apparatus from the separator. The purpose of this so-called "grader" is to initially grade the pulverulent material, re- 10 turning the large particles, called "tailings," back to the grinding-machine to be reduced and permitting the particles of sufficient fineness to pass on beyond the grader. In other words, this so-called "grader" serves as a screen 15 in that by regulating the valves in the spout of the exhaust-fan it is possible to cause material of varying degrees of fineness to be passed therethrough, say, up to a certain mesh, those particles of material exceeding 20 in size the desired mesh being returned to the machine for regrinding or to a suitable receptacle as finished product. It will be observed that the grinding-machine operating in a closed system will thoroughly reduce 25 the material. The vacuum in spout B can be regulated by the valve b. The dust-laden air entering the grader will be deflected laterally and downwardly, the tortuous passage it is compelled to follow resulting in the precipitation of heavier particles of material into 30 the pipe D, which connects with the feed end of the pulverizer. The outlet-pipe F being connected with the eye of an exhaust-fan will have a constant tendency to draw and 35 exhaust all the air and its carried particles of material through the grader. The amount of air admitted to the grader is controlled by the valves b and d, the available area through which said air is drawn into the fan being 40 controlled by the valve f.

It is well known that particles of material held in suspension in air rely upon the air resistance for their buoyancy and that if said particles of material were placed in a vacuum- 45 chamber wherein the air would offer no resistance to the action of gravity said particles of material would be practically dead, so far as their floating capacity is concerned. We take advantage of this natural law in effecting the grading action in the chamber C by exhausting the air from said chamber and creating a partial vacuum therein, so as to take away from the particles of material the sustaining properties of the air, rendering 55 them more susceptible to the action of gravity. Being introduced into a chamber from which the air is being constantly exhausted and wherein there exists a partial vacuum and being compelled to take a tortuous passage at the time of introduction into said chamber, the particles of material will immediately become more susceptible to the action of gravity when they reach the grading chamber, and the heavier particles will fall 60 and the lighter particles will be drawn into the pipe F to the exhaust-fan. By regulating the valve d the fineness of the particles

entering the pipe F can be controlled. If said valve is closed or nearly closed, it follows that there is no upward circulation of air through the pipe D. Therefore the heavier particles are not resisted in their descent, and a more finely-divided product will thus pass through the pipe F. If, on the other hand, the valve d is open to permit an upward circulation of air therethrough, the particles of material meeting with this resistance are held in suspension by the air passing upwardly through the pipe D, and consequently the material passing through pipe F is of a coarser 80 quality. The regulation of valve b is such that the opening controlled thereby is about sufficient to take care of the capacity of the grinding-machine without admitting an excess quantity of air at this point; but of course 85 it will be understood that the valve b being open full will affect the degree of fineness of the particles of material passing through the pipe F. However, it is not intended to use the valve b for the purpose of accomplishing 90 this, said valve being designed, primarily, to control the exit-opening from the grinding-machine, and thus goes more to accommodating the capacity of said machine than to controlling the quality of ground material passing beyond the bolter. The valve f is adjustable to regulate the discharge-opening from the grader according to the capacity of the fan, and while the opening controlled by this valve will affect the quality of material 95 passing therethrough said valve is not intended to be used for this purpose, we preferring to rely rather on the valve d, which is not only more accessible, but, depending upon conditions, can be manipulated as occasion requires—as, for instance, an excess of heavy particles falling into the pipe D would require the valve d to be opened to a greater extent, while a scarcity of material in pipe D would require that the valve d be 100 closed. The accessibility of valve d and its ease of manipulation is of advantage in the event of an irregular feed of material into the grinding-machine. If the material to be ground is not regularly fed and there is no 105 regulation of valve d, it follows that a variation in the quality of the product will result, which is undesirable. We do not claim the details of this grader in this application, as the same forms the subject-matter of an application filed contemporaneously herewith on December 17, 1900, Serial No. 40,176, the same being designated as "Case B."

The pipe H being the discharge-pipe from the exhaust suction-fan G leads into the head of a separator I, the details of construction of which are shown in Figs. 4 and 5. Referring now to these figures, it will be seen that the discharge-pipe enters the head of the separator on a parallel line with one of the 120 sides of the octagon, and the dust-laden air is forced to pass in a downward direction by the inclined deflecting-pipes i, leading from the head to the main body of the machine,

the particles of material being whirled around and by centrifugal force caused to hug the conical lower portion of the separator until they enter the discharge-spout J. This discharge-spout is provided with a valve j for well-understood reasons. In Fig. 1 we have shown scales upon which is arranged a bag for receiving the material from the discharge-spout J. The top of this separator is closed to the exterior, but receives a pipe K, which extends some distance down into the separator-chamber, the introduced end of said pipe being surrounded by the inner casing of the head k, whose lower end affords a point of attachment for the various inclined deflecting-pipes i. As stated before, the dust-laden air enters the chamber of this separator, and centrifugal force causes the particles of dust or most of them to hug the walls of the chamber until finally they are deposited in the discharge-spout J. In some classes of material, where it is possible to moisten the particles of dust in the air and to the extent that they absorb such moisture they become heavier and are more readily deposited in the discharge-spout, we introduce a steam-pipe L, having a jet at its ends, which jet throws the steam into the head of the separator at the point of introduction of the dust-laden air. We may also employ a perforated steam-pipe M near the lower end of the hood k and beneath the inclined deflecting-pipes i for the purpose of introducing steam into the separating-chamber at a point where the dust-laden air passes from the contracted discharge-mouth of the head into the larger conical chamber. We do not claim the details of this separator in this application, as the same forms the subject-matter of an application filed contemporaneously herewith on December 17, 1900, Serial No. 40,178, and designated "Case C." Any finely-divided particles of material in the separator which are not deposited in the discharge-spout J will pass upwardly through the pipe K, and instead of permitting said particles to escape to the exterior we prefer to lead said pipe K into an auxiliary collector N, the details of which are shown in Figs. 6 and 7. A deflector-plate n is used in advance of the pipe K, so as to impart a whirling motion to the incoming dust-laden air, causing the particles thereof to be deposited in the discharge-spout O, while the purified air escapes into the atmosphere through a pipe P. This pipe P extends down into the head of the auxiliary separator N some distance, as shown in Fig. 7. To prevent the particles of material deposited in the pipe O from being lost and to avoid making special provision to receive the same, we connect the lower end of said pipe O directly with the pipe F, leading into the eye of the suction-fan, so that the particles of material in pipe O are drawn into pipe F and forced by the fan G back into the separator I. This pipe O has a depending portion o, which serves as a pocket or chamber

for the collection of any water of condensation.

Of course it is obvious that in connection with some materials steam cannot be used, while in others it is not only permissible to use steam, but it is highly advantageous to do so.

It will be observed that with respect to the system above described the same is what might be termed a "closed" system—that is, substantially the same air is used over and over again—the pipe P being the only communication between the system and the exterior. However, this pipe is located at such distance from the means for circulating the air that it serves very well the purpose of a vent, supplying the air needed in the system upon the rarefaction at any point outside of the grader, and in the event that there is a surplus of air in the system the vent P will provide means of escape therefor.

Our improved collector and separator can be used with various material—in fact, in connection with all materials which are reduced to a powdered form—with relation to some of which it may be possible to use water in addition to steam, while others will have to be treated dry, as before stated.

It will be obvious that instead of connecting the spout D with the feed end of the pulverizer, whereby the tailings are returned to the machine, said spout can be led off into a suitable receptacle for collecting said tailings. Such an arrangement will be employed where it is desired to collect granulated material and separate the dust therefrom.

In pulverizing-machines employing revolving beaters we have observed in actual practice that the blows of the beaters on the material to be pulverized will effect the greatest pulverization, and if the material is left in the machine it will soon assume the speed of the beaters, so that the subsequent reduction thereof is carried on by friction. In our system instead of permitting the particles of material acted upon by the beaters to be carried around in the machine and worn out by friction we create a suction upon the machine at the discharge end thereof (opposite the feed end) and endeavor to take all the material from the machine whether or not said material is reduced to a sufficient degree of fineness. By doing this the capacity of the machine is greatly increased. These particles of material, both large and small, are drawn into the grader and caused to take a tortuous path. The vacuum in the grader being greatest at the lower end thereof will effect a quick separation of the heavier from the finer particles, said finer particles going off through the outlet-pipe F, which is of larger diameter, and into the eye of the exhaust-fan. The polygonal shape of the grader shown in the drawings lends itself to a ready separation of the particles of material by the formation of eddies in the corners thereof, in addition to which the sharp turn the dust-laden air is

compelled to take in passing under and around the deflector-plate creates eddies in the partial vacuum behind said plate, which greatly assists in the separation. The heavier particles, in the form of tailings, falling into the discharge-spout at the lower end of the grader pass into the feed end of the machine, the valve *d* being so regulated as to prevent the inrush of air, which might reduce the vacuum in the bottom of the grader. These tailings being thus returned to the machine are again subjected to the action of the beaters and pulverized, or partially so, said comminuted tailings again passing up through the discharge-pipe *B* and into the grader, and so on, this cycle of operations continuing until the material is reduced to a degree of fineness capable of being drawn out through the outlet-pipe *F*. Thus it will be seen that friction is not relied upon to reduce the material in the pulverizer, the actual blows of the beaters more quickly and readily reducing the material, while the suction on the mill keeps it free and clean and permits of the beaters acting upon a greater quantity of material than they could otherwise act upon without choking the machine. As the dust-laden air is forced beyond the exhaust-fan it enters the enlarged head of the separator through the inlet-pipe thereof, which is tangentially arranged, so that the air is forced to move in one direction around said head. Where the material is capable of being moistened in the head, this unidirectional movement permits of the dust-laden air remaining for a longer period in the head, so that the moisture will have an opportunity of becoming absorbed by the particles of material. When the dust-laden air is deflected downwardly, it does not lose any of its speed, and the polygonal shape of the casing of the separator enables the formation of small eddies in the corners thereof, which assist in freeing the air from its carried particles. It will also be seen that the air entering the pipe *K* is in a whirling state, which continues until the air is discharged into the auxiliary separator. In passing through the pipe *K*, which pipe is circular, the axis of the whirling air follows the axis of the pipe, so that in entering the auxiliary separator any particles of material carried by the air will spread until their direction of movement is changed by the curved deflector-plate in the auxiliary separator. The restraint thus placed upon the air and its carried particles produce what might be termed a "break," in that the air is forced to suddenly change its direction and in so doing more readily yields its carried particles and permits them to fall into the discharge-pipe leading from this auxiliary separator. Of course after "breaking" the air is given a circular motion in the auxiliary separator and by reason of the polygonal shape of said separator the eddies formed in the corners assist in freeing the air of its par-

ticles, centrifugal force being relied upon as the principal element in this separation.

We are aware that minor changes in the arrangement, construction, and combination of the several parts of our device can be made and substituted for those herein shown and described without in the least departing from the nature and principle of our invention.

Having thus described our invention, what we claim, and desire to secure by Letters Patent, is—

1. In a system for pulverizing and grading material, the combination with a machine for reducing the material to powdered form, a grader *C*, a spout leading from the reducing-machine into the grader, a spout *D* connecting said grader with the feed end of said machine, a pipe *F*, a fan *G* associated with the pipe *F*, a separator *I*, a pipe leading from the fan *G* into the separator, a discharge-pipe *J* for the separator, an auxiliary separator *N* opening to the atmosphere, a pipe *K* between the separators *N* and *I*, and a discharge-spout *O* leading from said auxiliary separator and connecting with the pipe *F*; substantially as described.

2. In a system for pulverizing and grading material, the combination with a machine for reducing the material to powdered form, of a grader for receiving the product thereof, an exhaust-fan connected to said grader, a separator for receiving the graded material under pressure, a discharge-spout leading from said separator, a valve in said discharge-spout, a pipe leading from said separator into an auxiliary separator, a pipe *P* leading from said auxiliary separator, a discharge-spout *O* leading from said auxiliary separator back to the exhaust-fan and a valve in said last-mentioned discharge-spout; substantially as described.

3. In a system for pulverizing and grading material, the combination with a machine for reducing material to powdered form, of a grader for receiving the product of said machine, a suction-fan for rarefying the air in said grader and discharging the dust-laden air under pressure into a separator, an auxiliary separator connected with said first-mentioned separator, a discharge-spout leading from said auxiliary separator and connecting with the discharge-fan, steam-pipes for admitting steam into the primary separator, and a pocket or chamber connecting with the discharge-spout of the auxiliary separator for collecting the water of condensation therefrom; substantially as described.

4. In a system for pulverizing and grading material, the combination with the machine for reducing the material to powdered form, of a pipe leading from said machine, a grader into which said pipe leads, a discharge-pipe leading from the grader into the eye of an exhaust-fan, another discharge-pipe leading from said grader for returning the heavier particles of material back to the feed end of

the pulverizing-machine, an exhaust-fan for creating a suction upon the machine and a vacuum in said grader, a separator into which the dust-laden air is forced from the exhaust-fan, a pipe leading from said separator for carrying off the excess air, said air entering said pipe in a whirling state, an auxiliary separator for receiving the whirling air from said pipe, and means in said auxiliary separator 10 for causing the air to "break" and change its direction; substantially as described.

5. An apparatus of the character described, comprising a reducing-machine, a grader C adjacent thereto, a pipe B leading from the 15 reducing-machine to the grader, a pipe D leading from the lower end of the grader back to the reducing-machine, a separator I, pipes F and H intermediate of the separator and grader and communicating with the same, and 20 a fan associated with the adjacent ends of the pipes F and H and adapted to draw material from the reducing-machine through the pipe B and grader C and force the same into the separator I; substantially as described.

25 6. An apparatus of the character described comprising a reducing-machine A having a receiving-hopper at one end thereof, a grader C supported above the reducing-machine, a pipe B leading from the reducing-machine 30 upwardly into the upper portion of the grader, a valve in said pipe, a pipe D leading from the lower end of the grader downwardly into the hopper of the reducing-machine, a valve in said last-mentioned pipe, and an exhaust 35 device associated with the upper end of the grader at a point remote from the discharge of the pipe B thereinto and adapted to draw material from the reducing-machine through the pipe B and grader C; substantially as 40 described.

7. An apparatus of the character described comprising a reducing-machine A having a receiving-hopper at one end, a grader C adjacent to said reducing-machine, a pipe B 45 leading from the top of the reducing-machine into one side of the grader C, a suction device at the opposite side of the grader and adapted

to draw material from the reducing-machine through the pipe B and grader C, and a valved pipe leading from the bottom of the grader 50 into the receiving-hopper of the reducing-machine; substantially as described.

8. An apparatus of the character described comprising a reducing-machine A, a grader C adjacent to said reducing-machine, a pipe 55 B leading from the reducing-machine into the upper portion of the grader, a pipe D leading from the lower portion of the grader back to the reducing-machine, a valve in said pipe D, and a suction device associated with the upper portion of the grader, at a point remote 60 from the discharge of the pipe B thereinto and adapted to draw material from the reducing-machine through the pipe B and grader C; substantially as described. 65

9. An apparatus of the character described comprising a reducing-machine, a grader, a pipe connecting the reducing-machine with the grader, a separator I, an exhaust-fan associated with the grader for rarefying the air 70 therein and forcing the dust-laden air into the separator, an auxiliary separator N, a communication between the two separators, and a pipe O leading from the auxiliary separator back to the exhaust-fan; substantially 75 as described.

10. An apparatus of the character described comprising a reducing-machine, a separator I, an exhaust-fan for withdrawing material from the reducing-machine and forcing the 80 same into said separator, an auxiliary separator N, a communication between the two separators, and a pipe O leading from the auxiliary separator back to the exhaust-fan; substantially as described. 85

In testimony whereof we hereunto affix our signatures, in the presence of two witnesses, this 14th day of December, 1900.

WILLIAM S. OSBORNE.
